COMBINED HAIR DRYER NOZZLE, BRUSH AND COMB

Michael G. Vitetta, 311 Fenimore Road,
Mamaroneck, N.Y. 10543

Filed Feb. 10, 1975, Ser. No. 548,331

Term of patent 14 years

Int. Cl. D28—03

U.S. Cl. D86—10 F

FIG. 1 is a front elevational view of a combined hair dryer nozzle, brush and comb showing my new design;
FIG. 2 is a right side elevational view thereof;
FIG. 3 is a rear elevational view thereof;
FIG. 4 is a top plan view thereof; and
FIG. 5 is a bottom plan view thereof.

I claim:

The ornamental design for a combined hair dryer nozzle, brush and comb, as shown.
